UNITED STATES PATENT OFFICE.

EVIA L. WISHON, OF PICHER, OKLAHOMA.

PULLING AND LIFTING DEVICE.

Application filed June 19, 1922. Serial No. 569,450.

To all whom it may concern:

Be it known that I, EVIA L. WISHON, a citizen of the United States, residing at Picher, in the county of Ottawa and State 5 of Oklahoma, have invented certain new and useful Improvements in Pulling and Lifting Devices, of which the following is a specification.

This invention relates to lifting and pulling devices, and the primary object of the invention is to provide a combined instrument which can be effectively used as a vehicle jack for raising vehicles or other loads to various heights and as a pulling device 15 for stretching wire or for pulling automobiles out of mud and the like.

Another object of the invention is to provide a novel tool embodying a supporting frame having associated therewith a sliding lifting standard, a rotatable drum, means for rotating the drum, and chains adapted to pass around the drum for detachable connection with either the lifting standard or with a device to be pulled.

A further object of the invention is to provide a novel means for anchoring the base or frame in position against movement when the improved pulling and lifting device is used for stretching wire or for pulling 30 automobiles out of the mud.

A further object of the invention is to provide a novel means for constructing the lifting standard whereby the same will form a guide and guard for the chain, which is 35 adapted to pass about the drum, when the chain is used for pulling vehicles out of the mud or the like.

A further object of the invention is to provide a novel and simple means for actuating the drum so that the said lifting standard can be easily actuated with a minimum 40 amount of effort.

A further object of the invention is to provide a novel drum for the chains, whereby 45 the necessity of the chains being wound about the drum is dispensed with, thereby eliminating the use of the large and cumbersome drum for the chains to wind about.

A still further object of the invention is 50 to provide a combined jack and pulling device of the above character, which will be durable and efficient in use, one that will be simple and easy to manufacture, and one which can be placed upon the market at a 55 reasonable cost.

With these and other objects in view, the invention consists in the novel construction, arrangement and formation of parts, as will be hereinafter more fully described, claimed and illustrated in the accompanying drawings, forming a part of this specification, in which drawings:

Figure 1 is a fragmentary plan view of the improved lifting and pulling device.

Figure 2 is a vertical longitudinal section 65 through the improved device, showing the same used as a jack.

Figure 3 is a front elevation of the improved device showing the same being used as a jack, parts of the device being broken 70 away.

Figure 4 is a detail plan view of the operating lever with parts thereof in section, for the drum of the device.

Figure 5 is a horizontal section through 75 the improved device taken on the line 5—5 of Figure 3.

Figure 6 is a horizontal section taken on the line 6—6 of Figure 3.

Figure 7 is a fragmentary detail perspective view of the lower portion of the lifting standard.

Figure 8 is a longitudinal section through 80 the improved device, showing the same in use as a pulling tool.

Referring to the drawings in detail, wherein similar reference characters designate corresponding parts throughout the several views, the letter A indicates the frame of the improved device; B, the novel 90 actuating drum; C, the means for operating the drum; D, the means for preventing retrograde movement of the drum; E, the lifting standard slidably mounted within the frame; F, and F' the lifting and pulling 95 chains; and G, a support to which the device can be attached when the same is being used as a pulling or stretching instrument.

The frame A includes a base plate 10 to which is secured upstanding vertical side 100 bars 11 and 12. The side bars or standards 11 and 12 have their inner faces channeled to provide guideways 13 for the reception of the lifting standards E which will be hereinafter more fully described. Suitable 105 braces or strips 14 are utilized for connecting the side pieces or standards 11 or 12 together as clearly shown in Figures 1, 2, and 3 of the drawings.

The frame A supports the drum B around 110

which is adapted to pass the pulling or lifting chains F, and F' and this drum includes the cylindrical body or hub 15 and the side flanges 16, which are of a disc shape. These disc shaped flanges 16 have their peripheries provided with teeth to provide ratchet wheels 17. The periphery of the drum is cast or otherwise formed to conform to the configuration of the links of the chains F and F', so that the said drums will constitute a combined lock and pull for the chains, eliminating the necessity of rigidly securing the chains to the drum and the winding of the chains about the drum. The periphery of the drum is provided with substantially oval shaped depressions 16' to receive the flat links of the chains and connecting grooves 15' for receiving the upright cross links of the chains. This drum is rotatably mounted upon a supporting shaft 18, which is supported by the side standards or pieces 11 and 12. If desired, these standards or pieces 11 and 12 may be provided with suitable bearings for receiving the said shaft. It is preferred that the terminals of the shaft 18 extend beyond the side standards or pieces 11 and 12 in order to form a fulcrum or rocking support for the actuating members C which will now be described.

The actuating member C includes a hand lever 20, the forward or inner end of which is bifurcated to provide a yoke 21, which is adapted to engage around the frame A. The yoke defines arms 22, which are provided with aligned recesses 23 for receiving the terminals of the shaft 18. One terminal of the shaft 18 is provided with a lock nut 24, while the other end can be provided with a removable cotter pin or the like 25'. This means effectively holds the shaft 18 in position against displacement. A guide way 25 is secured in any preferred manner upon the body portion of the lever 20 and slidably supports the dog 26 which is adapted to engage the ratchet wheels 17. This dog 26 is normally urged into engagement with the ratchet wheels 17 by means of an expansion coil spring 28 which is coiled about the shank 29 of the dog and bears respectively against the outer end of the dog and against a guide 30 provided for the shank 29 of the said dog 26. An operating handle 31 is pivotally secured to the handle of the lever 20, as at 32 and this handle is connected, by means of a link 33, with the shank 29 of the dog 26, and it can be seen that by pressing inwardly on the handle 31, the dog 26 can be slid outwardly and away from the ratchet teeth in order to permit the return movement of the lever to its lowermost position without movement of the drum B. It is obvious, however, that when the dog 26 engages the ratchet wheels 17, and when downward movement is imparted to the lever, the drum B will be rotated. Upon up-

ward movement of the lever 20, the dog 26 will simply ratchet over the ratchet wheels 17 and impart no movement to the drum B.

The means D for preventing retrograde movement of the drum B consists of a sliding dog 35 which can be mounted in suitable guides 36 secured to the standards or side pieces 11 and 12. This dog 35 is disposed below the ratchet wheels 17 on opposite sides of the ratchet wheels from the dog 26 and is normally urged into engagement with the periphery of the ratchet wheels by means of an expansion spring 37, which is coiled about the shank 38 of the dog 35. This spring bears respectively against the lower end of the dog 35 and against a guide way 39 formed for the shank 38 of the said dog. If desired, a handle 40 may be formed upon the dog 35 in order to permit the depressing thereof.

The lifting standard E is slidably mounted within the frame A and includes the side pieces 41 and 42, which are connected at their upper ends by means of a head 43 and their lower ends by means of a bottom plate 44. These side pieces 41 and 42 are disposed within the guide ways 13 formed in the standards or side pieces 11 and 12 of the frame A.

In order to permit free sliding movement of the lifting standard E, the side pieces 41 and 42 thereof are provided with slots 45 which receive the shaft 18. These slots 45 are in the nature of guide ways, as the shaft 18 forms a guide pin therefor.

The head 43 may have its upper surface concaved, as at 46, in order to permit the same to conform to the configuration of a vehicle axle or the like. An aperture 47 is formed centrally within the head 43 and forms a guide for the pulling chain F'.

The chain F is formed relatively short and is primarily intended to be used for lifting purposes, but can also be used for connecting the device to a support, when the device is being used as a pulling instrument. One end of the chain F can be provided with a hook 48 to permit the same to be connected to the lower end of the lifting standard E. The other end of the chain is placed partly about the drum with the chain links in the openings 15' and in the connecting slots 16' which effectively holds the same in place, during operation of the drum.

When the improved pulling and lifting device is to be used as a jack, the hook 48 is hooked over the bill of a hook 49, which is secured to the plate 44, carried by the lower end of the lifting standard E.

In use, the device is placed under the vehicle in the ordinary manner, with the lifting head 43 in engagement with the axle. Pressure is then applied to the outer end of the lever 20 and upon downward movement thereof, the drum B will be rotated, as here-

tobefore described, which will pull up the lifting chain, and thus lift up the lifting standard E and effectively raise the vehicle axle or other work.

- 5 When it is desired to return the lifting standard to its normal lowered position, it is merely to depress the dog 35 against the tension of the coil spring 37 and push down upon the lifting standard E.
- 10 When the improved lifting and pulling device is to be used for pulling purposes, the base plate 10 is anchored in any preferred manner to a support, such as a support G as shown in Figure 8 of the drawings. This support has been shown to be in the nature of a post, but it is to be understood that the base plate can be secured to any rigid member. The chain F can be utilized for anchoring the device to the support, and the same is extended about the support and through guide notches or slots 51 formed in the ends of the base plate 10. The upper face of the plate 10 is provided with cross notches 52 in which the cross links of the chain are adapted to rest, thus connecting the chain and the device firmly to the support. Now, when the device is to be used for pulling the chain F is disconnected from the hook 49 and removed from the device and used for holding the device in position as stated and the relatively long chain F' is extended through the aperture 47 in the head 43 which forms a guide for the same, and one terminal of the chain is then secured in any preferred manner to the device to be pulled. The inner end of the chain is partially passed about the drum as heretobefore described. The lever 20 is then operated and the chain is pulled inwardly by the drum B and this effectively exerts a pulling action upon the device, to which the chain F' is attached.

From the foregoing description, it can be seen that a simple and efficient device has been provided for use either as a lifting jack or as a pulling tool.

Changes in details may be made without departing from the spirit or scope of this invention; but,

50 I claim:

1. A lifting and pulling device comprising a frame including a base plate, anchoring means carried by the base plate, a slide mounted within the frame including a lift-

ing head having a guide opening therein, a drum rotatably mounted within the frame, means for rotating the drum, a pulling chain passed about said drum, the opening in the head forming a guide for the chain when the device is used for pulling purposes.

2. A pulling and lifting tool comprising a frame including a base plate, and side pieces extending upwardly from the base plate in spaced relation to each other, the inner faces of the side pieces being grooved to provide guide ways, a slide member mounted in the frame and having side arms slidably fitting in the guide ways, a rotatable shaft carried by the frame and extending beyond opposite sides thereof, the arms of the slide being slotted to receive the shaft, a drum mounted upon the shaft and having heads extending through the space between the side piece of said frame and provided with ratchet teeth about their peripheries, a lever rockably mounted upon the extended end portions of the shaft, a sliding dog carried by the lever for engaging the ratchet teeth of the drum, and a flexible member passed about the drum adapted to detachably engage one end of the slide.

3. In a lifting and pulling device, a frame open at its upper end and including a base plate and standards having the inner faces thereof grooved to provide channel ways, a sliding member passing into the frame and having spaced arms fitting into the channel ways and having longitudinally extending slots, a shaft rotatably carried by the standards of the frame and extending through the slots formed in the arms of the lifting standard, a drum carried by the shaft, ratchet discs connected with the drum and extending downwardly between the standards of the frame, a lifting head connecting the outer ends of the arms of the lifting member, a hook carried by the lower end of the lifting member, a chain passed about the drum and having a hook provided at its free end and adapted to engage said hook, a dog slidably carried by the frame arranged to engage the ratchet discs to prevent retrograde movement thereof, a lever rockably mounted upon the shaft, and a dog slidably carried by the lever for engaging the ratchet discs.

EVIA L. WISHON.
